Samuel B. Williamson
By his Attorney
Albert Smith

UNITED STATES PATENT OFFICE.

SAMUEL B. WILLIAMSON, OF WESTPORT, CONNECTICUT.

DIAPHRAGM FOR SOUND-PRODUCING INSTRUMENTS.

1,418,998.

Specification of Letters Patent. Patented June 6, 1922.

Application filed October 20, 1920. Serial No. 418,230.

To all whom it may concern:

Be it known that I, SAMUEL B. WILLIAMSON, a citizen of the United States of America, and a resident of Westport, county of 5 Fairfield, State of Connecticut, have invented certain new and useful Improvements in Diaphragms for Sound-Producing Instruments, of which the following is a specification.

10 One of the objects of my invention is to provide a diaphragm which is very delicate and responsive in its nature so as to take up the vibrations of the sound initiating instrumentalities and likewise equally delicate and 15 accurate in reproducing same.

Another object of my invention is to so form the diaphragm as to eliminate to a greater degree than heretofore attained the nasal qualities of the voice and at the same 20 time to do away with all scratchy noises; and in carrying this phase of my improvement into effect I provide a sound screen, or sifter, integral with, and midway of, the diaphragm structure, which will arrest and eliminate 25 these undesired vibrations and permit the undiluted original tones to arrive at, and depart from, the outer, or sound, delivering surface.

I further in my invention and improved 30 diaphragm contemplate and attain a much greater vibratory activity than heretofore achieved in any similar instrumentality of like dimension; in fact I secure an amplitude of vibration equal to that which would ordinarily be obtained in a diaphragm of four or 35 five times the area; that is under present constructions.

Another, and very important, object secured by me in the engineering of my present 40 improvement is that I provide a structure which will secure the harmonious reproduction of orchestras, so that the orchestra, as a whole, is truly and accurately reproduced and the accentuating of any special 45 instrument is entirely avoided.

Another object of my invention, which I will hereinafter explain at large, is the separation of the sound producing zone of my diaphragm from that part of the diaphragm 50 which is attached to its supports; and in this way and through this arrangement the dia-

phragm is permitted to vibrate unhampered and unhindered by its supporting agencies: the great difficulty experienced in this respect was, and is, that the diaphragm, in vibrating, transmitted part of its activities to the box, or container, which latter would thereupon set up a sympathetic and more or less independent action resulting in conflicting sounds: in creating zones, as I will explain, I am enabled to intervene and entirely obviate this drawback. In order to achieve this I will here state, although I will explain it more fully further on, that the structure which receives sifts and reproduces the vibration must be, as a unit, integral; that is to say, homogeneous: a built-up or laminated diaphragm always results in individually developed vibrations and consequent interfering and discordant sounds. The laminations 55 meddle with one another and instead of amplifying and clarifying the sounds serve only to muddle and befog: a thick instead of a clear sound; a burr instead of a bell.

Specifically I provide a cylindrical diaphragm formed of fibrous paper with a suitable binder so blended and disposed as to result in a homogeneous mass, and on both faces of the diaphragm I impose a suitable coating of very fine glue.

In constructing my diaphragm I provide a relatively large centrally located vibrating zone. This zone is as heretofore indicated, formed of fibrous material with a suitable binder and a coating on each face; it is my 85 desire and purpose to limit the vibrations to this central zone and not permit them to be communicated to the box or case of the phonograph; to achieve this I provide a concentric zone immediately outside of and contiguous to the central zone of a conformation which will operate to halt and cut off the sound vibrations, and I accomplish this by effecting a compression of the material so that when the vibrations proceeding radially 90 outward from the center of the disc reach this depressed portion they will not get across; in other words this is a dead non-vibrating annular moat which refuses passage to the progress of the vibrations.

The outer edge or periphery of the diaphragm may be formed in various ways as I

will explain, but I cannot too strongly accentuate the necessity and importance of the annular moat aforesaid.

This depression or moat also serves to 5 limit the vibrations and prevents them creeping, and it also in a sense is a sort of hinge for the outer edge of the central zone.

Referring to the accompanying drawings which form part of this specification,

10 Figure 1 represents a view partly in section of a phonograph instrument.

Figure 2 indicates the same implement on the line II—II. Figure 1.

15 Figure 3 is a cross section of my improved diaphragm as it is shaped preliminarily.

Figure 4 is a similar view of the diaphragm after it has been treated with the coating material.

20 Figure 5 shows the conformation of the diaphragm after it has been subject to compression: in this view appears the main central vibrating zone, the depressed concentric zone surrounding same which depression is designed and intended for shutting off and 25 stopping the outward radial travel of the vibrations of the central zone thereby preventing said vibrations from reaching the phonograph case or box and setting up independent and conflicting vibrations; in this 30 view is also shown the outer or peripheral zone positioned in the complete structure to be embraced and held in position by the diaphragm supporting agencies of the phonograph case. In this figure also I show the 35 central perforation designed to receive the needle arm.

Figure 6 represents the diaphragm with the immediate supporting agencies consisting of the peripheral rings; this view 40 also shows the central attachment.

Figures 7 and 8 show modified forms of diaphragms.

At 12 is the peripheral rim which in cross section is full size, the same size in cross 45 section as the central zone 13. Between the central zone 13 and the peripheral rim 12 is the annular depression 14 positioned concentric with the central zone and formed by pressing in upon the diaphragm from both 50 sides. This annular depression 14 is arranged in the outer portion of the diaphragm and contiguous to the final outer rim 12. The physical effect of this distribution of zones is that when the central area 55 becomes agitated by the needle arm the amplitude of the resulting vibrations of the diaphragm will be greatest at the central point, the vibrations tending to decrease as they approach the periphery; nevertheless 60 at the periphery there will be some activity which if unsuppressed will be communicated to the parts of the phonograph structure which serve as peripheral supports; this latter defect, which attaches to all present 65 forms of phonographs, I purpose eliminat-

ing by means of the depression 14 for when the radial travel of the vibrations, moving from the central point outwards, reach this depression they are halted as said depression by reason of its position and inherent rigidity will operate as a stop; the vibrations in other words will not get across the zone 14.

In Figure 7 I show a modified form of depression; here the annular groove 15 is on one side of the disc only: in Figure 8 is another form: in this instance it is a sort of platform 16. The principle in all of these is the same however and that is a wave stop between the central vibrating zone and the phonograph box.

At 17 is the central perforation to accommodate the screw 18 for attaching the needle arm 19.

At 20 are peripheral rings of rubber or other suitable material and these latter embrace and retain the disc at its outer edge.

At 21 is the needle held in the needle arm 19 by adjusting screw 22 and at 23 is shown the record disc. These latter are conventional forms and need not be enlarged upon.

Having thus described my invention the following is what I claim as new and useful therein and desire to secure by Letters Patent.

1. A circular sound producing diaphragm 95 formed throughout of fibrous material with a compressed concentric zone between the center and periphery.

2. A sound producing diaphragm formed throughout of homogeneous fibrous material 100 and comprising a main central portion and a concentric compressed depression positioned between the periphery and the center.

3. A sound producing diaphragm formed throughout of homogeneous fibrous material 105 and comprising a main central portion and a concentric compressed depression positioned relatively nearer the periphery than the center.

4. A sound producing diaphragm formed 110 throughout of fibrous material, and comprising a main central un-compressed vibrating zone, and a concentric zone positioned relatively near the periphery sufficiently compressed to permit independent vibrating activities of the central zone.

5. A sound reproducing diaphragm formed throughout of fibrous material, and comprising a main central un-compressed vibrating zone, and a concentric compressed depression positioned exterior to the said main zone.

6. A circular sound producing diaphragm 115 formed throughout of homogeneous fibrous material with central and peripheral zones 120 of equal thickness and provided with an intermediate zone of lesser thickness but equal cross-sectional mass.

7. A circular sound producing diaphragm 125 formed throughout of homogeneous fibrous

material, and comprising a main central vibrating zone, with a concentric exterior zone of greater density than the central zone.

8. The method of making diaphragms for sound producing instruments which consists in providing a cylindrical disc of fibrous

paper having a binder so blended and dis-

posed as to result in a homogeneous mass, applying on both faces of the diaphragm a coating of very fine glue and finally by compression forming a zone of diminished cross-section contiguous to the periphery of the diaphragm.

SAMUEL B. WILLIAMSON.
